UNITED STATES PATENT OFFICE.

BARTLETT P. LUCE, OF BOSTON, MASSACHUSETTS.

LAMP-BURNER.

SPECIFICATION forming part of Letters Patent No. 487,020, dated November 29, 1892.

Application filed February 1, 1892. Serial No. 419,906. (No model.)

To all whom it may concern:

Be it known that I, BARTLETT P. LUCE, of Boston, in the county of Suffolk and State of Massachusetts, have invented certain new 5 and useful Improvements in Lamp-Burners, of which the following is a specification.

This invention relates to that class of lamp-burners organized to hold a chimney having a cylindrical base. Heretofore burners organized to hold chimneys of this form have been provided with spring-arms adapted to bear with a yielding pressure on the surface of the chimney, in some cases the internal surface, but more generally the external surface, each arm being independent of the others and exerting a pressure on the chimney due only to its own resilience. In the course of time these independent arms lose their elasticity, and consequently do not grasp the chimney with sufficient firmness. Hence it often happens that the chimney is loosely held and falls accidentally from the burner.

My invention has for its object to enable a chimney having a cylindrical base to be 25 clamped or grasped so that there will be no liability of its being so loosely held as to fall accidentally from the burner.

To this end my invention consists in a lamp-burner having a chimney seat or support, diverging elastic arms projecting upwardly from said seat, a flexible or yielding chimney-clamp connected with said arms and consisting of a band having downturned arms connected with said seat, and means for compressing the clamp upon the said elastic arms, the clamp being adapted to hold the chimney above said seat and with a yielding pressure by its own elasticity and by the elasticity of those portions of the arms that project above 35 the clamp, whereby expansion of the chimney by heat is permitted and the clamp is adapted to conform to variations in the size of chimneys, all of which I will now proceed to describe and claim.

45 In the accompanying drawings, forming a part of this specification, Figure 1 represents a side view of a burner provided with my improvement and showing a lamp-chimney in

place. Fig. 2 is a perspective view of the burner.

The same letters of reference indicate the same parts in all the figures.

In the drawings, *a* represents the base or flange of a lamp-burner, on which the lower end of the cylindrical lower portion or base 55 of the chimney *b* rests.

The general construction of the burner has nothing to do with my invention, the same being confined to the means, presently described, for grasping and holding the chimney. 60

In carrying out my invention I secure to the base or flange *a* a clamp formed to embrace the cylindrical base *b* at a point above the lower end thereof and provided with means whereby it may be positively compressed or tightened upon said chimney-base, so as to firmly hold the same, as shown in the drawings. I employ a single jaw composed of a curved wire *c*, having its ends bent downwardly and constituting inclined arms *c' c'*, 70 connected with the base or flange *a*. The jaw *c* bears on the outer side of the elastic arms *f f*, attached to and projecting upwardly from the base *a*, said arms being formed to bear upon the exterior of the chimney-base 75 after the manner of the arms usually employed as the sole means of holding the chimney. It will be seen that by forcing a sleeve *g* upwardly upon the arms *c' c'* the jaw *c* will be compressed and caused to force the arms 80 *f* inwardly against the surface of the chimney. The jaw *c* in this case is supported at a point opposite the arms *c' c'* by means of a wire standard *c²* rising from the base or flange *a* and attached at its upper end to the 85 jaw *c*; or the jaw *c* may be secured directly to the arms *f*.

I claim—

A lamp-burner having a chimney seat or support *a*, diverging elastic arms projecting 90 upwardly from said seat, a flexible or yielding chimney-clamp connected with said arms and consisting of a band having downturned arms connected with said seat, and means for compressing the clamp upon the said elastic 95 arms, the clamp being adapted to hold the

chimney above said seat and with a yielding pressure by its own elasticity and by the elasticity of those portions of the arms that project above the clamp, whereby expansion of the chimney by heat is permitted and the clamp is adapted to conform to variations in the size of chimneys, as set forth.

In testimony whereof I have signed my

name to this specification, in the presence of two subscribing witnesses, this 30th day of January, A. D. 1892.

BARTLETT P. LUCE.
